UNITED STATES PATENT OFFICE

CAROLUS L. EKSERGIAN AND TALMON A. DAVENPORT, OF DETROIT, MICHIGAN, ASSIGNORS TO BUDD WHEEL CO., OF PHILADELPHIA, PENNSYLVANIA, A CORPORATION OF PENNSYLVANIA

DESIGN FOR A WHEEL

Application filed April 18, 1932. Serial No. 43,538. Term of patent 14 years.

To all whom it may concern:

Be it known that we, CAROLUS L. EKSERGIAN and TALMON A. DAVENPORT, citizens of the United States, residing at Detroit, in the county of Wayne, and State of Michigan, have invented a new, original, and ornamental Design for a Wheel, of which the following is a specification, reference being had to the accompanying drawing, which forms a part hereof.

Figure 1 is a side elevation of a wheel showing our new design.

Figure 2 is a detail perspective view of the

wheel body of the design shown in Figure 1. Figure 3 is a profile view.

Figures 4 and 5 are spoke sections on the lines 4—4 and 5—5 respectively, of Fig. 3.

We claim:

The ornamental design for a wheel as shown.

Signed at Detroit, county of Wayne, State of Michigan, this 14th day of April, 1932.

CAROLUS L. EKSERGIAN.
TALMON A. DAVENPORT.
